UNITED STATES PATENT OFFICE.

THOMAS O. BATES, OF LIVERPOOL, ENGLAND.

MACHINERY FOR MAKING WAFER BISCUITS, CUP WAFERS, AND SIMILAR ARTICLES FROM LIQUID.

Application filed August 24, 1921. Serial No. 494,778.

To all whom it may concern:

Be it known that I, THOMAS OWEN BATES, a subject of the King of England, and residing at Liverpool, in the county of 5 Lancaster, England, have invented Improvements in Machinery for Making Wafer Biscuits, Cup Wafers, and Similar Articles from Liquid, of which the following is a specification.

10 This invention has reference to machinery for making wafer biscuits, cup wafers, and similar articles, and it relates more particularly to that type in which a plurality of cooking "plates" are connected 15 in series, and are passed through an oven with the biscuit material enclosed within them, and then brought out of the oven after cooking, and opened, and re-charged with batter or like material, and closed, and 20 the operation repeated; in which type of apparatus, in some cases, the plates are run on tracks one below the other in entering, and returning from the oven, which may be heated by gases or other heating 25 medium.

In a machine according to this invention, between the adjacent edges of each set of "plates", there is introduced a shield or separating medium, which prevents the

30 steam generated from the batter or material introduced into a hot plate, after charging, issuing from same between the upper and lower plates, just prior to closing, from blowing batter therefrom into the open 35 succeeding plate on reaching it; and this partition or shield, the sides of which the adjacent ends of the two plates may practically touch, may be of an inverted U-type—say of metal—carried by brackets or 40 arms on the inside of the plate connecting links or devices. These arms or brackets extend inwards horizontally or substantially so, so as to be in line with, or in the same plane as the axles of the plates in 45 order to clear the lower track rails of the machine, as they move along the track and turn round at the ends, and the inward ends of the arms or brackets project upwards into the shields, and are connected 50 by pins say to same; movement longitudinally being allowed so as to compensate for expansion and contraction.

The invention is illustrated in the annexed drawings, in which Figure 1 is an 55 end view of the machine showing a parti-

tion or shield; Figure 2 is a cross section of the shield; Figure 3 is a side elevation of the machine; and Figure 4 a plan.

Referring to the drawings, 1 and 2 are the upper and lower plates of the machine, 60 the upper one of which is hinged at 3, and these plates are each mounted on to cross shafts 4 fixed to the lower plate, and having wheels 5 on their ends which run on tracks 6, on the inside of the main frames 65 7 of the machine; the axles of the successive plates being connected together by coupling links 8 which form couplings between the plates.

The machine thus far described in connection with the drawings is of known construction.

The shield or partition is marked 10, and it is carried by brackets 11 fixed on the inner sides of the coupling links 8, and the 75 form of the partition or shield is an inverted narrow trough of sheet metal, as seen in Figure 2, and the heads of the brackets 11 lie within the ends of the shield, and the shield is secured to the brackets by rivets 80 or the like, longitudinal movement being allowed by giving freedom of play in the connections, so as to allow for expansion and contraction.

In the machines of the kind referred to, as heretofore made, comprising a number of "plates" successively charged with matter or fluid after the cooked articles have been removed, the plates being hot (and being heated by gas or other means in the known 85 way), the batter begins to boil before the upper cover 1 comes down and is closed, and the steam issues in a thin stream from the rear edge of the newly charged plate, (as well as other edges), and this stream 90 of steam is horizontally projected on to the leading open edges of the next "plates" being charged with batter, and this batter is blown about by the steam, and often a large proportion lost; but by the present 95 invention, the batter being so introduced is not interfered with and cannot be blown away, being prevented by the shield or partition 10 between the plates.

What is claimed is:

1. In a wafer biscuit making machine, a movable series of plates, and a baffle interposed between adjacent plates to prevent a fresh charge introduced in one set of plates from being interfered with by steam gen- 110

erated from the charge of the preceding plate, said baffle projecting above the material receiving plane of the plates and being wholly free of connection with any of the 5 plates.

2. In a wafer biscuit making machine having a movable series of plates, an inverted U-shaped metallic member interposed between adjacent plates of the series 10 to prevent a fresh charge introduced in one

set of plates from being interfered with by steam generated from the charge of the preceding plate.

In testimony whereof I have signed my name to this specification in the presence 15 of two subscribing witnesses.

T. O. BATES.

Witnesses:

BARBARA JAQUES,
MABEL PECK.
